UNITED STATES PATENT OFFICE

CHARLES A. FRENCH, OF RIVERSIDE, ILLINOIS

STEAM PRESSURE REGULATING DEVICE

Application filed October 14, 1929. Serial No. 399,686.

This invention relates to a pressure regulating device for steam generating systems. More particularly, it relates to cooperating means for regulating the feed water supply for and the heat supplied to such a system.

One object of the invention is to construct a device for regulating the feed water supply to a boiler by the pressure generated therein. Another object is to regulate the amount of heat supplied to the boiler by the pressure in the feed water line, and indirectly by the pressure in the boiler. Another object is to cooperatively arrange the regulating means, so that the burner supplying heat to the boiler cannot be made to operate unless feed water is being pumped into the boiler at a predetermined pressure. A minor object is to provide a time interval between a reduction in the feed water pressure and the cutting off of the fuel supply from the burner. Other objects will be apparent from the detailed description to follow.

The objects of the invention are accomplished by an arrangement of cooperatively arranged pressure operated means. A bypass valve is arranged in the feed water supply line, and means operated by the boiler pressure are provided for actuating the bypass valve when the boiler pressure reaches a predetermined amount for which the valve is set to operate. A plunger arranged to operate a valve controlling the fuel supply to the heating means for the burner is positioned in a chamber in fluid communication with the feed water line. Upon release of the feed water pressure, due to by-passing the feed water or for any other reason, such as failure of the feed water pump, the plunger is operated by a spring member to by-pass the fuel being supplied to the heating means. The same plunger may also operate a switch, which controls the current for driving the fan motor.

A bleed line, communicating with the plunger chamber, allows a small portion of the water in the plunger chamber, which is under high pressure, to continually escape. A check valve is positioned between the high pressure feed water line and the chamber, to prevent return flow from the chamber

when the pressure drops in the feed water line. This provides for a time lag between the reduction of pressure in the feed water line and the action of the plunger in its chamber. The time interval is controlled by the valve in the bleed line.

A preferred embodiment of the invention is hereinafter described and illustrated in the drawing, where:

Figure 1 is a diagrammatic sketch of a steam generating and consuming system in which the invention is embodied; and,

Figure 2 shows the essential parts of a regulating device embodying the elements shown in Figure 1 as constructed in a unitary housing.

In Figure 1, a boiler 1 is supplied with heat by a burner 2. The burner is provided with an air supply fan 3 driven by a motor 4. A fuel pump 5, driven by any suitable means, not shown, is positioned to draw fuel from a reservoir 6 and force it through a pipe line 7 to the burner 2.

Steam generated at a suitable pressure in the boiler is delivered by a high pressure pipe 8 to a steam engine 9. The exhaust from the engine is led to a condenser 10, and the condensate is delivered to a hot well 11.

A feed water pump 12, driven by any suitable means, not shown, pumps water from the hot well 11 through a high pressure feed water pipe 13 to the boiler 1. A check valve 14 is positioned in the feed water pipe 13 adjacent the boiler. A branch pipe 15 from the feed water pipe 13 communicates with a valve chamber 16 in which a by-pass valve 17 is held in closed position by a spring 18. The valve has an integral stem 19, which extends into a low pressure casing 20 adjacent the valve chamber and in communication therewith. The casing contains a cylindrical member 21 having a closed bottom 22 and an outwardly extending flange 23 at the top. A spring 24 resting on the bottom of the casing 20 is positioned to press upwardly against the flange 23 at the top of the member 21.

A tubular member 25 depends from the top of the low pressure casing 20 into the cylindrical member 21. A packed plunger 26 is positioned in the tubular member 25.

and is adapted to engage the bottom 22 of the cylindrical member 21. The top of the tubular member is in communication with the pipe line 8 carrying the full boiler pressure.

5 The valve chamber 16 communicates through a pipe 26' with a second chamber in the form of a plunger cylinder 27. A check valve 28 is positioned in the pipe 26' to permit flow only in the direction of the 10 plunger cylinder. A small bleed pipe 29, controlled by a valve 30, connects the plunger cylinder with the low pressure casing 20. A small drain pipe 31 connects the top of the plunger cylinder with the low pressure 15 casing.

A packed plunger 32 is positioned in the plunger cylinder 27 and has an extending stem 33 positioned to engage a lever 34 fulcrumed on a pivot 35. The lever 34 is held 20 against the stem 33 of the plunger by a spring 36 positioned on the opposite side of the pivot 35. A second plunger cylinder 37 is arranged to control the fuel supplied to the heating means. A plunger 38 has an upward extension 39 engaged by the lever 34, and a lower and downwardly extending stem 40. The 25 stem 40 has a valve member 41 attached thereto, which is normally kept in closed position against a seat 42 by a spring 40' resting on 30 the bottom of the plunger cylinder.

A connecting pipe 43 communicates with the lower part of the plunger cylinder 37 and with the fuel pipe 7. A fuel return pipe 44 connects with the plunger chamber above 35 the valve 41 positioned therein, and discharges into the fuel tank 6. A switch 45 has an operating lever 46 operatively connected to the lever 34 by a cord 47. The 40 switch is positioned in the current supply line by which the fan motor is operated.

Figure 2 shows the elements making up the pressure regulating device previously described as part of the steam generating system shown in Figure 1. It will be noted that 45 in Figure 2 the elements are shown housed in and on a unitary housing. The plungers 26 and 38 are shown as being provided with a series of packings to adapt them for the high pressure developed in boilers such as used in 50 steam vehicles. The valve compartment 16 is provided with a threaded plug 16^a for adjusting the tension on the valve spring 18 and for gaining access to the valve chamber. A similar plug 37^a is positioned in the bottom 55 of the plunger cylinder 37 for the same purposes.

In the operation of the regulating device, the steam generating system is put into operation by starting the feed water pump 12, 60 the fuel pump 5, the fan motor 4, and igniting the burner 2. Steam is generated and pressure builds up in the steam line 8. The steam is consumed by the steam engine 9, or is used for other purposes, and the exhaust steam 65 is delivered to the condenser 10. The con-

densate collects in the hot well 11 and is recirculated by the feed water pump.

Pressure from the feed water line is transmitted to the plunger cylinder 27, and the plunger 32 is held out against the lever 34. 70 In this position of the lever 34, the spring 40' in the plunger chamber 37 holds the fuel by-pass valve 41 in closed position.

When the pressure in the steam line 8 reaches a predetermined amount for which 75 the device is adjusted to function, the plunger 26 is forced down against the bottom of the cylindrical member 23. As soon as the slack is taken up between this member and the valve stem 19, the valve 17 is opened and the 80 feed water is by-passed into the low pressure casing 20. From this casing it runs back into the hot well through a pipe 13^a. When the valve 17 opens, the pressure in the pipe 26' leading to the plunger cylinder 27 is reduced. 85 The check valve seats and prevents the return flow back into the pipe 26'. The valve 30 in the bleed pipe 29 is adjusted so that a small amount of water continuously leaks from the plunger cylinder 27 into the low 90 pressure casing 20. As soon as the valve 28 seats, the flow of water through the bleed line 29 reduces the pressure operating against the plunger 32 and it descends in the plunger chamber. This feature of the device gives a 95 time lag between the reduction of pressure in the feed water line and the cutting off of the fuel supply. When the plunger 32 is pushed down by the spring 36 acting on the lever 34, the plunger 38 is also actuated. The 100 valve 41 in the plunger cylinder is opened and the fuel supplied from the pump 5 is by-passed back into the fuel tank.

The switch 45 is adjusted so that the downward movement of the lever 34 cuts off or 105 reduces the speed of the fan motor.

When the pressure falls in the boiler, the actions just explained are reversed. The valve 17 is seated when pressure is reduced by the plunger 26, and pressure is built up 110 in the feed water pipe 13. This pressure is transmitted to the plunger cylinder 27, raising the plunger 32. This action closes the fuel by-pass 41 and starts the fan motor by operating the switch 45. In case the feed 115 water pump fails for any reason, or, if the pressure in the feed water pipe leading to the boiler fails for any reason, it will be seen that the heat supplied to the boiler is automatically reduced until a predetermined pressure 120 is again built up in the feed water pipe.

It will, therefore, be seen that I have devised a comparatively simple arrangement of elements for positively controlling the feed water supply for and the heat supplied to a 125 steam generating system, and that departure from the specific form illustrated is possible within the scope of the claim.

What is claimed is:
In an arrangement of the character de- 130

scribed, the combination of a boiler having a generator therein, heating means in said boiler, electric operating means for causing said heating means to function, an electric circuit controlling said operating means, a water tank, a pumping medium adapted to deliver water from said tank to said generator, a feed pipe through which water from said pumping medium passes to said generator, a branch on said feed line, a control device on said branch, a pressure responsive means in said control device against one side of which pressure is adapted to be exerted by water in said branch, a stem in said control device movable with said pressure responsive means, a switch movable by said stem to closed position when pressure is exerted against said pressure responsive means from said feed pipe, and means for moving said pressure responsive means, said stem and said switch, to open said switch when the water pressure against said pressure responsive means ceases, said switch being arranged in said electric circuit so that when opened said heating means is extinguished.

25 In testimony whereof I affix my signature.
CHARLES A. FRENCH.
